R. B. BENJAMIN.
FUSE PLUG.
APPLICATION FILED MAY 4, 1918.

1,374,349.

Patented Apr. 12, 1921.

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

FUSE-PLUG.

1,374,349.

Specification of Letters Patent. Patented Apr. 12, 1921.

Application filed May 4, 1918. Serial No. 232,437.

To all whom it may concern:

Be it known that I, REUBEN B. BENJAMIN, a citizen of the United States, residing at Chicago, in the county of Cook and State 5 of Illinois, have invented new and useful Improvements in Fuse-Plugs, of which the following is a full, clear, concise, and exact description, reference being had to the accompanying drawing, forming a part of this 10 specification.

My invention relates to fuse plugs.

Among the objects of my invention are to provide an improved construction of fuse plug furnished with a plurality of fuses which can be brought successively into the circuit, which construction shall be durable and efficient in use, cheap to manufacture, simple and compact in construction, and easy to manipulate. Further objects will 20 appear from the detailed description to follow and from the appended claims.

In the drawings, in which one embodiment of my invention is shown—

Figure 1 is a transverse section on the 25 line 1—1 of Fig. 3;

Fig. 2 is a view looking down on Fig. 3;

Fig. 3 is an axial section of the plug on the line 3—3 of Fig. 1;

Fig. 4 is an axial section on the line 4—4 30 of Fig. 2;

Fig. 5 is a transverse section of the partition members on the line 5—5 of Fig. 4;

Fig. 6 is a transverse section on the line 6—6 of Fig. 3;

Fig. 7 is a side elevation of the fuse magazine;

Fig. 8 is a section similar to Fig. 6, showing a construction which places two of the fuses in the circuit at the same time; and

Fig. 9 is a fragmentary view of an indicating portion of the device.

In order to give a general idea of the plug, it is here stated that it is of the type which can be screwed into an Edison socket; that 45 it is provided with a fuse magazine which carries a plurality of fuses, which fuses may be successively brought into the circuit, so that when one is blown the magazine carrying the fuses can be shifted so as to bring 50 another fuse into the circuit; and that it may readily be provided with means whereby more than one of the fuses may be brought into the circuit simultaneously.

This last provision enables the plug to be easily changed to meet different requirements. For instance, if the plug is made with six fuses, one of which is suitable for a ten ampere current, it can very easily be changed so that two fuses will be brought into the circuit, which will make it right 55 for a twenty ampere circuit; and it can also be easily changed so that three of the fuses will be brought into the circuit, in order to make it suitable for a thirty ampere circuit.

It is also here stated that in the embodiment of the invention shown the insulation is made up entirely of sheet material, such as fiber, which can be readily stamped out, so that a very cheap construction is obtained.

It is also stated that the plug is so constructed that the screwing of the plug into the socket will tend to force into better electrical connection the contacts which bring 75 the fuses into the circuit.

Referring now to the drawings in detail, the fuse plug shown comprises an insulating base 10 built up of pieces of sheet material, such as fiber, which may be readily stamped 80 out, a sheet-metal contact member 11 secured to and supported by the insulating base 10, a plurality of fuses 12 secured to and supported by the insulating base 10, a threaded shell contact 13 into which the insulating base 10 carrying the center contact 11 and the fuses 12 can be slipped and with which it has a snap connection (indicated at 14), a combined thumb-piece and housing member 15 for screwing the threaded shell 85 13 into the socket and for housing the electrical parts and preventing the escape of gases when the fuse is blown, and an insulating ring or sleeve 16 between the threaded shell 13 and the thumb-piece 15 for insulating the thumb-piece from the threaded shell contact 13.

The insulating base 10 comprises a fiber sleeve 17, three partition members 18, 19, and 20 located inside the sleeve 17 and fitted 100 together so as to divide the space within the sleeve into six chambers, one for each fuse; a fiber disk 21 which supports the center contact 11 and which is riveted to the fiber partition members 18, 19, and 20 105 and which closes the upper ends of the

chambers formed by the partition members 18, 19, and 20; and two fiber disks, 22 and 23, respectively, riveted to the fiber partition members 18, 19, and 20 for closing the lower ends of the chambers formed by the partition members, and for supporting the contacts to which the outer ends of the fuses 12 are connected.

In order that the disks 21, 22 and 23 may be riveted to the partition members 18, 19, and 20, they are provided with holes through which lugs 24 and 25 on the partition members extend, the lugs being riveted over after the disks are in place. The partition member 20 is notched about one-third of its length at both top and bottom; the member 18 is notched about two-thirds of the way down from the top; and the member 19 is notched about two-thirds of the way up from the bottom, so that the three partition members can be fitted together, as shown in Figs. 3 and 4, by slipping the partition member 19 down on the partition member 20 from the top, and slipping the partition member 18 up on the partition member 20 from the bottom.

The center contact is a hollow sheet-metal rivet, riveted to the insulating disk 21. The six fuses are formed by crossing three strips of fusible material, these strips being secured in electrical connection with the center contact 11 by being clamped between a sheet-metal plate 26 and the flange 27 of the center contact 11.

The chamber formed by the tubular portion of the rivet 11 provides a space in which the three strips which form the fuses can cross each other without being crushed when the fuses are clamped in place. For holding the fuses 12 in place and properly positioning them, a disk 28 of insulating material is placed beneath the metal disk 26, the disk 28 being provided with notches 29 to receive the fuses.

The lower ends of the fuses 12 are secured in soldering wells formed by sheet-metal cup-shaped members 30 positioned in recesses 31 in the disk 23, and having flange portions 32 clamped between the disks 22 and 23. The ends of the fuses are secured in place in the soldering wells by placing solder 33 in the cup-shaped portion of the soldering wells, around the ends of the fuses.

For completing the electrical connection between the center contact 11 and the shell contact 13 through the fuses 12, a contact member 34 is secured to the transversely-extending bottom portion 35 of the shell contact 13 in position to enter any one of the recesses 31 in the disk 23 to engage the corresponding soldering well 30, thereby completing the circuit through the corresponding fuse.

The contact member 34 may be a cup-

shaped metal member having a neck portion extending through an opening in the bottom 35 of the threaded shell and having a portion 36 flanged over for securing the contact to the shell.

If it is desired that two fuses shall be in the circuit simultaneously, two contact members 34 are provided, as indicated in Fig. 8, which enter two of the recesses 31 and engage two of the soldering wells, so that two of the fuses are brought into the circuit.

The bottom 35 of the threaded shell contact is pierced in four places, indicated at 37, 38, 39, and 40. If it is desired that only one fuse shall be brought into the circuit at a time, the contact member 34 is secured only in the opening 37; if it is desired that two of the fuses shall be brought into the circuit simultaneously, the contact members 34 are secured both in the aperture 37 and the aperture 38; if it is desired that three of the fuses be brought into the circuit simultaneously, the contact members 34 are secured in the apertures 37, 39, and 40.

The apertures 37 and 38 are located diametrically opposite each other, and the apertures 37, 39, and 40 are located 120 degrees apart.

For insulating the bottom 35 of the threaded shell from the thumb-piece 15, an insulating disk 41 of fiber or other suitable material is secured to the thumb-piece member 15.

For preventing the magazine part of the plug from becoming separated from the shell contact part 13 in handling, a quick-detachable connection is provided between these two parts. This fastening is similar to what is known as a "glove fastening." It comprises a sheet-metal member 42 having a flat portion 43 clamped between the insulating disk 41 and the bottom of the thumb-piece member 15, and a spring ball-shaped portion 44 for engagement with a sheet-metal socket portion 45 which is secured to the insulating disk 23. The ball-shaped portion 44 is provided with a number of slits 46 in its side, which enable the ball-shaped portion to be compressed for insertion into the socket member 45, the ball-shaped portion expanding after it has been placed in the socket, to hold the magazine part of the plug in position with respect to the shell contact 13 and the thumb-piece portion 15.

This snap connection between the fuse magazine and the shell contact prevents them from becoming separated in handling, and at the same time permits of their ready separation when it is desired to shift the fuse magazine to bring a new fuse into the circuit.

The threaded shell contact 13 is cut away, as indicated at 47, adjacent the contact mem-

ber or contact members 34, in order to prevent the formation of an arc from one fuse to another through the threaded shell contact when a fuse is blown. The threaded shell contact 13, the insulating ring or sleeve 16, and the thumb-piece 15 are secured to each other by striking up portions of all three of these members at various points in their circumference, as indicated at 48. 5 These struck-up portions may be provided adjacent the contact member or contact members 34, and such struck-up portions may be provided with indicating means 49 (Fig. 9) to enable the user of the plug to easily determine just where the contact members 34 10 are located, when inserting the fuse magazine in the shell 13. 15

In using the plug, the fuse magazine is slipped into the shell contact 13 and the two 20 parts are snapped together by means of the quick-detachable connection 14, the contact member 34 entering one of the recesses 31 and engaging the corresponding soldering well 30. The plug is then screwed into a 25 socket until the center contact 11 is in engagement with the center contact of the socket, the screwing in of the shell 13 forcing the contact 34 firmly into engagement with the soldering well 30 to form a good 30 electrical contact.

If the current is so heavy that the fuse is blown, the plug is screwed out of the socket, the fuse magazine is detached from the shell contact and inserted in the shell contact in 35 new position, so as to bring another one of the fuses 12 into the circuit.

For heavy current it may be desirable that two of the fuses be brought into the circuit. In this case two contacts 34 are provided, 40 diametrically opposite each other, for engagement with two of the soldering wells 30, respectively. If these two fuses are blown, the fuse magazine is shifted so as to bring two more fuses into the circuit.

In case it is desired that three of the fuses shall be brought into the circuit simultaneously, three contact members 34 are provided at points 120 degrees apart, for engagement with three of the soldering wells 45 30, respectively. If these three fuses are blown, the fuse magazine is shifted to bring the other three fuses into the circuit.

I claim as new and desire to secure by Letters Patent of the United States:

55 1. A fuse plug comprising a threaded shell contact, a combined fuse and center contact support comprising a cylindrical shell of insulating sheet material telescoping inside said threaded shell contact, and a disk of insulating sheet material extending across the inner end of said insulating shell, a center contact secured to said disk, and a fuse located in said insulating shell and carried by said fuse support and electrically connected 60 with said center contact, said disk being se-

cured to and carried by said insulating shell, and removable therewith as a unit from said threaded shell.

2. A fuse plug comprising a cylindrical threaded shell contact, a support for a center contact and fuse comprising a cylindrical shell of insulating sheet material telescoping inside said threaded shell contact, and a disk of insulating sheet material extending across the outer end of said insulating shell, a contact member secured to said disk, a center contact carried by said support, and a fuse located in said insulating shell and electrically connected with both of said contacts, 70 said disk being secured to and carried by 75 said insulating shell, and removable therewith as a unit from said threaded shell.

3. A fuse plug comprising a cylindrical threaded shell contact, a support for a center contact and fuse comprising a cylindrical shell of insulating sheet material telescoping inside said threaded shell, a disk of insulating sheet material extending across the inner end of said insulating shell, and a second disk of insulating sheet material extending across 85 the outer end of said insulating shell, a center contact supported by said first insulating disk, a second contact supported by said second disk, and a fuse electrically connected with both of said contacts and located in 90 said insulating shell, said disk being secured to and carried by said insulating shell, and removable therewith as a unit from said threaded shell.

4. A fuse plug comprising a cylindrical threaded shell contact, a support for a fuse and center contact comprising a cylindrical shell of insulating sheet material telescoping inside said threaded shell, a disk of insulating material across the outer end of said insulating shell, a contact supported by said disk, two partition members located in said insulating shell and extending at an angle to each other to form, with said insulating shell, a chamber extending longitudinally of 100 the plug, a center contact carried by said support, and a fuse located in said chamber and electrically connected with both of said contacts.

5. A fuse plug comprising a cylindrical threaded shell contact, a support for a fuse and center contact comprising a cylindrical shell of sheet insulating material telescoping inside said threaded shell contact, a disk of insulating material extending across 115 the inner end of said insulating shell, a second disk of insulating material extending across the outer end of said insulating shell, and two partition members extending at an angle with respect to each other and forming, with said insulating shell, a chamber extending longitudinally of 120 said plug, a center contact supported by said first insulating disk, a second contact supported by 125 said second insulating disk, and a fuse located 130

cated in said chamber and electrically connected with both of said contacts.

6. A multiple fuse plug comprising a cylindrical threaded shell contact, a plurality of fuses located within said threaded shell contact, means for insulating said fuses from each other comprising a plurality of interfitting partition members of insulating sheet material lying substantially in intersecting planes through the axis of said plug, an insulating disk at the inner end of said plug having a plurality of openings therein, said partition members having portions extending through said openings, and a center contact supported by said disk and electrically connected with said fuses.

7. A multiple fuse plug comprising a cylindrical threaded shell contact, a plurality of fuses located in said threaded shell contact, means for insulating said fuses from each other comprising a plurality of interfitting partition members of insulating sheet material lying substantially in intersecting planes through the axis of said plug, a disk of insulating material extending across the outer ends of said partition members, and a plurality of contacts supported by said disk and electrically connected with said fuses, said disk having a plurality of openings therein, said partition members having portions extending through said openings.

8. A fuse plug comprising a cylindrical threaded shell contact, a fuse located in said threaded shell contact, a substantially circular disk extending across said threaded shell contact, a contact supported by said disk and electrically connected with said fuse, and an insulating partition member of sheet material lying substantially in a plane through the axis of said plug, said disk having an opening therein and said partition member having a portion extending into said opening.

9. A fuse plug comprising a cylindrical threaded shell contact, a fuse located in said threaded shell contact, a disk of insulating material extending across the inner end of said threaded shell contact, a center contact supported by said disk and electrically connected with said fuse, a second insulating disk extending across the outer end of said threaded shell contact, a second contact supported by said second disk and electrically connected with said fuse, each of said disks having an opening therein, and a partition member of insulating sheet material extending between said disks and having a portion extending into each of said openings.

10. A fuse plug comprising a cylindrical threaded shell contact, a fuse located within said shell contact, two disks of insulating material, and a metal soldering-well member having a flange portion clamped be-

tween said insulating disks to which the end of said fuse is soldered.

11. A fuse plug comprising a threaded shell contact, a fuse located in said threaded shell contact, a contact member electrically connected with said shell contact, and a dished metal soldering well to which the end of said fuse is soldered, said soldering well having a contact portion for engagement with the contact member connected with the shell contact.

12. A fuse plug comprising a threaded shell contact, a fuse located in said threaded shell contact, a contact member electrically connected with said threaded shell contact, an insulating disk having an opening therethrough into which said contact member may extend, a soldering well having a cup-shaped portion located in said opening and having a contact portion for engagement with said contact member, the end of said fuse being soldered in said cup-shaped portion.

13. A fuse plug comprising a cylindrical threaded shell having a transversely-extending portion at the outer end thereof, said transversely-extending portion having an opening therein, a contact member secured in said opening, a fuse located in said threaded shell, and a second contact member electrically connected with said fuse for engagement with said first contact member.

14. A multiple fuse plug comprising a threaded shell contact having a transversely-extending portion at the outer end thereof, having a plurality of openings therein, a plurality of contact members, one secured in each opening, a plurality of fuses located within said threaded shell contact, and a plurality of contact members, one for each of said fuses, for engagement with said first plurality of contacts.

15. A multiple fuse plug comprising a threaded shell contact, a tubular center contact, and a plurality of fuse members crossing each other within the tubular portion of said center contact.

16. A fuse plug comprising a threaded shell contact, a tubular center contact, a plurality of fuse members crossing each other within the tubular portion of said center contact, and a plate of conducting material for engaging said fuse members and clamping them against said center contact.

17. A multiple fuse plug comprising a threaded shell contact, a plurality of fuses located in said threaded shell contact, means for insulating said fuses from each other comprising a plurality of interfitting partition members of insulating sheet material lying substantially in intersecting planes through the axis of said plug, said fuses comprising fuse members crossing each other substantially in the axis of said plug, and

means for spacing said fuses comprising a disk of insulating material extending across the ends of said partition members.

18. A multiple fuse plug comprising a threaded shell contact, a plurality of fuses located in said threaded shell contact, means for insulating said fuses from each other comprising a plurality of interfitting partition members of insulating sheet material 10 lying substantially in intersecting planes through the axis of said plug, said fuses comprising fuse members crossing each other substantially in the axis of said plug, and means for spacing said fuses comprising a disk of insulating material extending across the ends of said partition members, said disk being provided with a plurality of notches, one for each fuse.

19. A multiple fuse plug comprising a threaded shell contact, an insulating fuse carrier having a plurality of chambers therein, a plurality of fuses located in said chambers, said chambers having openings to the outside of said fuse carrier, a contact electrically connected with said threaded shell contact for electrical connection with said fuses, said threaded shell contact being cut away adjacent said contact to prevent arcing when a fuse is blown.

20. A fuse plug, comprising a cylindrical threaded shell contact, a support for a center contact and fuse, comprising a cylindrical shell of insulating sheet material located in said threaded shell contact, a disk 35 of insulating sheet material extending across

the outer end of said insulating shell and secured thereto and carried thereby, a contact member secured to said disk, a center contact carried by said support, a fuse located in said insulating shell and electrically connected with both of said contacts, an insulating disk extending across said threaded shell contact and secured thereto, and quick detachable fastening members carried by said disks for securing said support in place in said cylindrical threaded shell contact.

21. A fuse plug, comprising a cylindrical threaded shell contact, a support for a center contact and fuse, comprising a cylindrical shell of insulating sheet material located in said threaded shell contact, a disk of insulating sheet material extending across the outer end of said insulating shell and secured thereto and carried thereby, a contact member secured to said disk, a center contact carried by said support, a fuse located in said insulating shell and electrically connected with both of said contacts, an insulating disk extending across said threaded shell contact and secured thereto, and quick detachable fastening members carried by said disks for securing said support in place in said cylindrical threaded shell contact, said quick detachable connections comprising a ball and socket connection.

In witness whereof, I have hereunto subscribed my name.

REUBEN B. BENJAMIN.
